MULTIWAY ELECTRICAL CONNECTOR OR SIMILAR ARTICLE

Samuel S. Fortino, New York, N. Y., assignor to
Gem Electric Mfg. Co., Brooklyn, N. Y.

Application April 9, 1951, Serial No. 14,764

Term of patent 14 years

(Cl. D26—1)

To all whom it may concern:

Be it known that I, Samuel S. Fortino, a citizen of United States of America, residing at 2220 Pearsall Avenue, in the county of Bronx and State of New York, have invented a new, original, and ornamental Design for Multiway Electrical Connector or Similar Article, of which the following is a specification, reference being had to the accompanying drawing, forming part thereof.

In the drawing:

Fig. 1 is a front view of a multiway electrical connector, showing my new design;

Fig. 2 is a view of one end of said connector;

Fig. 3 is a view of the opposite end of said connector; and

Fig. 4 is a top view of said connector.

The front and back of the connector are identical and the top and bottom of the connector are identical in appearance.

I claim:

The ornamental design for a multiway electrical connector or similar article, substantially as shown and described.

SAMUEL S. FORTINO.
